UNITED STATES PATENT OFFICE

WALTER E. EBLING, OF NEW YORK, N. Y., ASSIGNOR TO E. P. REED & CO., OF ROCHESTER,
NEW YORK, A CORPORATION OF NEW YORK

DESIGN FOR A SHOE

Application filed March 2, 1931. Serial No. 38,894. Term of patent 14 years.

To all whom it may concern:

Be it known that I, WALTER E. EBLING, a citizen of the United States, residing at No. 101 West 58th Street, in the borough of Manhattan, city, county, and State of New York, have invented a new, original, and ornamental Design for a Shoe, of which the following is a specification, reference being had to the accompanying drawings, forming a part thereof.

Fig. 1 is a plan view of the shoe with the upper in a closed position, showing my new design; and Fig. 2 is a plan view of the shoe showing the upper in an open position.

I claim:

The ornamental design for a shoe substantially as shown and described.

WALTER E. EBLING.
